ABSTRACT OF THE DISCLOSURE

A digital electronic organ wherein a digital representation of an organ pipe wave shape is stored in a memory. A frequency synthesizer activated by a manual or pedal key produces a clock frequency at Nf , where f is the frequency of the note selected, and N is the number of sample points in the stored wave shape. The digitized wave shape is read out repetitiously at the generated clock frequency and converted to analog form to produce a musical note having a wave shape corresponding to that stored in the memory. Circuitry is provided to sum digitally notes which are played simultaneously; to shape each note in attack and decay using digital operations; and to read out stored multiple wave shapes to implement harmonic and mutation stops.

BACKGROUND OF THE INVENTION**Field of the invention**

The present invention relates to an electronic musical tone generation system in which tones are manually selected. More specifically the invention relates to an electronic organ wherein a digital representation of an organ pipe or other musical wave shape is stored in a memory and accessed repetitiously at a selectable rate to produce a selected musical note.

Description of the prior art

With the even increasing market for electronic organs, there is a similar increase in the demand for realism in the sound produced by these instruments. Electronic simulation of the complex musical waveforms characteristic of air driven organ pipes represents a difficult technical problem. The problem often is made more difficult by the requirement that the electronic organ also be capable of simulating the sounds of many other instruments such as pianos, flutes, horns, strings, bells, etc. In the past, various techniques have been used to accomplish such synthesis, with varying degrees of success.

Most common of the prior art approaches toward electrical simulation of an air driven organ pipe sound involves the utilization of a plurality of oscillators. The oscillators produce substantially sinusoidal tones at the fundamental frequency of the note being keyed and at the various harmonics contained in the corresponding organ pipe note. The outputs of the oscillators are mixed, with appropriate amplitude weighting, to produce a complex waveform representative of the air driven pipe. This multiple oscillator approach has met with varying success, depending on the degree of sophistication used in filtering and shaping the outputs of the individual oscillators and in the number of oscillators used to produce the complex sound.

The oscillator technique clearly has many limitations. First, there is the large number of oscillators required. In better quality prior art electronic organs, 300 to 400 oscillators may be used in a single instrument. Second, the oscillators' outputs basically are sine waves, hence considerable shaping and balancing circuitry is required to mix the outputs appropriately to simulate an organ

2

pipe sound. Moreover, slight drift in one or more of the oscillators may cause a considerable reduction in realism of the complex wave form prepared. Third, it is difficult to produce an identical complex waveform for each note of the scale. For example, the oscillators used to produce the waveform for a particular stop for the key of C_1 (i.e., the note C is the first octave) may, when combined, produce a different wave shape than will the oscillators used to produce the note of B_1 with the same stop. This problem is complicated by the requirement that the same note in different octaves also have the same wave shape.

Another complication is that most air driven pipe organs have more than one rank of pipes (e.g., flute, bourdon, diapason, etc.). In electronic organs, it is desirable to simulate several of these ranks of pipes. When multiple oscillators are employed, this requires that the shaping and weighting circuits for combining the oscillator outputs be different for each of the various ranks of pipes simulated.

A different problem complicating the use of oscillators to produce a simulated organ sound is the requirement that when the harmonic stops are selected (for example, 4', 2' or 1' flute or diapasons), when a particular key is struck, the note which must be sounded is a harmonic of the key depressed. For example, if key C_2 is pressed with a 4' stop, the note which actually must be sounded is $(2 \times C_2) = C_4$. When oscillators are used to produce the organ tones, considerable additional circuitry is required to insure that the proper note is sounded when the harmonic stops are selected. The problem is even more difficult with the mutation stops (e.g., 2½' flute or 1½' diapason), where the note sounded is not harmonically related to the key which is depressed.

Another prior art approach to simulation of air driven organ pipe sounds involves the actual recording of such sounds, either on magnetic tape or (more commonly) on a movie film sound track. The electronic organ then utilizes some type of read-back device, either a photosensor or magnetic pickup, to reproduce the recorded notes as the manuals or pedals are keyed. While these techniques enable accurate reproduction of organ tones, they require recording of the organ sound for each note. Furthermore, they have the inherent limitation of being electromechanical, and of not permitting completely electronic operation.

Among the other techniques used to generate sounds in prior art electronic organs was a toothed wheel chopper. The wheel rotated at selectable rates and produced a note by mechanically chopping a light beam sensed by a photocell. The shape of the teeth determined the shape of the generated waveform. Again, this technique has the inherent problem of being mechanical, and has the additional problem that the generated wave shape is not accurately representative of a tone produced by an organ pipe.

Once an organ note has been synthesized, it is necessary to shape appropriately the rise time (attack) and fall time (decay) of each note, thereby simulating the inherent mechanical lag in initiating and ending the sound produced by an air driven organ pipe. In prior art electronic organs, such attack and decay characteristics usually are produced by charging and discharging a capacitor to provide a logarithmically increasing or decreasing reference voltage level. The amplitude of the generated note then was normalized against this reference voltage to produce a sound having appropriate attack and decay characteristics. Clearly, this technique limited the selection of differing attack and decay characteristics (both in time and rate), and if unusual attack characteristics were required, for example, to simulate cymbals or bells, considerable additional shaping circuitry was required.

Further, note that each of these prior art electronic organs was analog in operation, and hence not easily adapted to utilization of the considerable digital micro-electronic technology which has been developed in recent years.

The present invention overcomes these and other limitations of the prior art, and provides an electronic musical synthesizer or organ which is digital in its operation. In a preferred embodiment, the inventive organ stores in digital form a wave shape which is representative of each rank of organ pipes to be simulated. This stored digital representation is used to generate musical notes (as selected by the manual and pedal keys) having essentially identical waveform characteristics regardless of what note (in any octave) is being played. Moreover, only a single frequency standard may be utilized, and this frequency standard does not determine the wave shape of the produced note.

The inventive digital electronic organ permits simplified implementation of both harmonic and mutation stops, and permits controlled selection of the attack and decay characteristics of the produced musical notes. Moreover, any number of waveforms, representative of different ranks of pipes, can be employed without requiring additional oscillators or frequency standards. The device is substantially electronic in its operation and, being digital, easily lends itself to implementation by batch fabricated microelectronic techniques.

SUMMARY OF THE INVENTION

In accordance with the present invention, there is disclosed a digital electronic musical synthesizer or organ capable of reproducing accurately all of the functions and tonal qualities of an air driven pipe organ or other musical instrument. The invention utilizes a wave shape memory in which is stored a digital representation of a waveform representative of the wave shape produced by an organ pipe of given rank or the wave shape of any other sound desired to be reproduced, musical or otherwise. The digital representation is stored as a plurality of binary words, each word representing the amplitude (or amplitude increment) at respective ones of a plurality of wave shape sample points.

To produce a musical note, a selected manual or pedal key is depressed. This closes a switch which gates out from a frequency synthesizer a clock signal having a frequency Nf , where f is the frequency of the selected note, and where N corresponds to the number of sample points in the stored digital wave shape representation. This clock signal is used as the time base for repetitiously reading out from the memory the digital words representing the wave shape. Since one period of the representative wave shape is represented by N words, and the read-out is at the rate Nf , the audio signal produced when the digital words are converted to analog form will have the desired frequency f . The same wave shape thus may be read from the digital memory regardless of what note is struck, and each note produced will have the same wave shape (although, of course, at different frequencies).

If two or more notes are struck at the same time, the wave shape in digital form is constructed from the memory at rates corresponding to the notes selected. It is not necessary that such wave shape be read out of the memory at such rate, although in this embodiment such is done. The digital values at each wave shape sample point for all the selected notes are summed in an appropriate summing circuit prior to conversion to an audio tone by a digital to analog converter. It is recognized that individual channels may be provided to sum selected voices or groups of voices for conversion to audio tones.

Attack and decay control circuitry is provided in association with each note produced by reading out the wave shape memory. The decay circuitry functions by shifting the digital words to the right by a programmed number of positions. This accomplishes division of the wave shape amplitude increments, and when appropriately pro-

grammed, facilitates logarithmic decay. Attack is provided by a similar program in which the shifted words are subtracted from the same word unshifted to get an exponentially increasing amplitude at the start of a note. Such attack and decay control, combined with the capability to reproduce the wave shape of any sound, permits the inventive musical tone generation system to synthesize a wide variety of special musical or tonal effects.

Although many notes can be constructed from a single period (or even a half period) of the wave shape, by storing more than one period of a wave shape and accessing at the rate at which a single period normally is read out, harmonic or mutation stops may be facilitated. Thus, 4', 2', 1', 1 1/2', and 2 1/2' stops may be produced simply by storing in the memory the appropriate number of periods of the wave shape representation. In addition, by storing several representative wave shapes in the memory (and selecting use of stop tabs, which is read out), various ranks of organ pipes can be synthesized.

Thus, it is an object of the present invention to provide an electronic musical instrument capable of providing a variety of musical notes and sounds.

It is another object of this invention to provide a digital electronic organ.

Another object of the present invention is to provide a musical instrument in which a digital representation of a wave shape is stored and repetitiously reconstructed to produce a musical note.

Yet another object of the present invention is to provide an electronic organ in which a characteristic organ wave shape is stored in digital form in a memory and read out repetitiously at a clock rate controlled by manual or pedal keys.

Yet another object of the present invention is to provide an electronic musical tone generation system in which tones are manually selected and wherein a plurality of tones may be produced by reading out repetitiously, but at different rates, the same wave form stored in a digital form in a memory.

A further object of this invention is to provide an electronic organ in which selection of a particular rank of pipes to be simulated is accomplished by selecting which digital representation of a waveform is to be read from a memory.

A further object of the present invention is to provide a technique for simulating harmonic or mutation stops of an organ.

A further object of the present invention is to provide an electronic organ wherein the attack and decay characteristics of the tones being generated are controlled by programmed arithmetic operations on a repetitious digital representation of a wave shape.

These and other objects and features of the invention will become apparent in conjunction with the following description and drawings which are included for illustrative purposes only.

BRIEF DESCRIPTION OF THE DRAWINGS

FIG. 1 is a simplified block diagram of the inventive digital electronic organ.

FIG. 2a shows a typical organ wave shape, a digital representation of which may be stored in the wave shape memory included in the electronic organ shown in FIG. 1.

FIG. 2b is a graph of the amplitude increments of the typical wave shape shown in FIG. 2a, as measured at the indicated sample points.

FIG. 2c shows a possible digital representation of the amplitude of the wave shape of FIG. 2a as measured at the sample points of FIG. 2b.

FIG. 2d shows a typical digital representation of the amplitude increment of FIG. 2b; such a digital representation may be utilized in the wave shape memory of the electronic organ of FIG. 1.

FIG. 3 is a block diagram of a frequency synthesizer which, as shown in FIG. 1, may be utilized in the present invention. The frequency synthesizer produces output

clock signals at frequencies which are a given multiple of the frequency of the note selected on the organ manual or pedal keys.

FIG. 4 is a simplified block diagram of one embodiment of the wave shape memory and recycling read control circuits included in FIG. 1. In the embodiment of FIG. 4, a fixed diode array is utilized as the wave shape memory.

FIG. 5 graphically represents the digital outputs which may be obtained from the wave shape memory of FIG. 4 when two notes are keyed simultaneously; in particular:

FIG. 5a shows the digital representation read at a rate corresponding to the first of the two notes selected.

FIG. 5b shows the digital representation read at a rate corresponding to the second of the two notes selected.

FIG. 5c is the summation of the digital representations shown in FIGS. 5a and 5b.

FIG. 5d is the analog wave shape resultant when the summed digital values of FIG. 5c are converted to analog form by the digital to analog converter included in FIG. 1.

FIG. 6 is a curve of the typical attack, sustain and decay characteristics of a single note played on an organ.

FIG. 7 illustrates the decay which may be achieved by a programmed shift operation on the digital wave shape representations read from the wave shape memory of FIG. 4.

FIG. 8 is a simplified block diagram of a circuit for insuring that a note, produced when a key is depressed, will be continued for a sufficient time after the release of the key to permit decay shaping.

FIG. 9 is a simplified block diagram of a possible implementation for the attack and decay control circuitry of the inventive electronic digital organ of FIG. 1.

FIG. 10 is a typical waveform showing the logarithmic attack which may be implemented by programmed shifting and subtraction of the digital words read from the waveform memory of FIG. 4.

FIG. 11 is a graph showing another attack wave shape which may be produced by appropriately programming the attack and decay control circuitry of the present invention.

FIG. 12 is a schematic representation of a memory storage allocation scheme useful for simulating harmonic and mutation stops in accordance with the present invention.

DESCRIPTION OF THE PREFERRED EMBODIMENT

A simplified block diagram of the inventive digital electronic organ is illustrated in FIG. 1. As indicated therein, a switch associated with each organ manual or pedal key is associated with an input lead to frequency synthesizer 10. Thus, e.g., when the manual key for C in the first octave (C₁) is depressed, a keyboard switch is closed, and an input to frequency synthesizer 10 appears on line 11. Similarly, depression of the key associated with the note B in the first octave (B₁) provides an input on line 12, while depression of the key associated with the note C in the eighth octave (C₈) provides an input along line 13.

As will be described more fully hereinbelow in conjunction with FIG. 3, frequency synthesizer 10 provides a discrete clock frequency output signal for each input from a selected keyboard switch. For example, if keyboard switch C₁ is selected, frequency synthesizer 10 will provide an output along line 14 having a clock frequency NC₁ where N is an integer and C₁ represents the frequency of the musical note C in the first octave. (The specific value of N will be defined hereinbelow.) Similarly, if keyboard switch (B₁) is depressed, frequency synthesizer 10 will provide an output along line 15 having frequency NB₁ (where N is the same integer as above, and B₁ represents the frequency of the musical note B in the first octave).

In the same way, depression of keyboard switch (C₈) will provide an output from frequency synthesizer 10 along line 16 at clock frequency NC₈, where N is the same integer and C₈ represents the frequency of the key of C in the eighth octave. If more than one keyboard switch is depressed simultaneously, frequency synthesizer 10 will provide a like plurality of outputs. Thus, if keyboard switches (C₁) and (B₁) both are depressed at the same time, frequency synthesizer 10 will provide outputs simultaneously on both of lines 14 and 15.

Referring still to FIG. 1, it will be noted that the outputs from frequency synthesizer 10 are fed, by way of read control assigner 20, to recycling read control circuits 22a, 22b . . . 22n. The number of recycle read control circuits 22 contained in a particular organ is a matter of design choice, however, in the embodiment shown one such recycling read control 22 is used for each note played simultaneously. Typically, a particular system may have 10 recycling read control circuits 22 since it is unlikely that more than ten manual or pedal keys will be depressed simultaneously.

Read control assigner 20 serves the functions of reorganizing the presence of a clock signal on one of the output lines (e.g., lines 14, 15 or 16) from frequency synthesizer 10 and of connecting that output line to a recycle read control circuit 22 which is not then in use. The manner in which the read control assigner 20 accomplishes this function analogous to the selection of an unused input or output device by an on-line computer, and applicable logic circuitry is well known to those skilled in the computer art.

Wave shape memory 24 contains a digital representation of one or more wave shapes typical of those which would be obtained from various ranks of air driven organ pipes. As described hereinbelow in conjunction with FIG. 4, each wave shape is stored in an appropriate digital form for subsequent processing. For example, a wave shape may be stored as 48 eight-bit words, each eight-bit word representing the amplitude of the wave shape at a discrete sample time.

When a particular keyboard switch is depressed, the clock frequency produced by frequency synthesizer 10 serves as the time base for the assigned recycling read control 22. Read control 22 in turn repetitiously reads out the stored digital representation of the wave shape, one word at a time, at a rate corresponding to the clock signal received from frequency synthesizer 10. By selecting the integer N to equal the number of words in the digital representation stored in wave shape memory 24, the entire wave shape will be read out repetitiously at exactly the frequency of the keyed musical note. Thus the output of wave shape memory 24 comprises one or more musical notes, in digital form, each note having a wave shape corresponding to the wave shape stored in memory 24, and a frequency corresponding to that of the selected notes.

The foregoing partial description of FIG. 1 will be understood more clearly by way of example. If the stored wave shape is represented by 48 words, then N=48. Suppose the manual key (C₁) is depressed, frequency synthesizer 10 will receive an input on line 11 and will provide an output clock signal at frequency 48 C₁=(48×32.70) Hz. Read control assigner 20 will assign this signal to recycling read control 22n (which assigner 20 determines it is not in use). Read control 22n then will read out repetitiously the 48 word digital representation in wave shape memory 24, one word at a time at the rate of (48×32.70) words per second, corresponding to the clock signal from synthesizer 10. Since 48 words comprise a complete period of the stored waveform, the waveform period will be repeated at a rate of 32.70 Hz., exactly the frequency of the selected note C₁.

Referring still to FIG. 1, note that if several different wave shapes are stored in wave shape memory 24, the one read out may be selected by means of stop tabs 25. Each

such stored waveform e.g., may be characteristic of a different rank of organ pipes.

Attack and decay control circuitry 26 (see FIG. 1) operates on the digital signal from wave shape memory 24 in such a way as to shape the rise time and fall time of each note being generated. Finally, summing means 28 combines the plurality of notes which may be struck on the keyboard simultaneously. Summing means 28 thus produces a single digital output representing the sum of the wave forms associated with each note in a chord. Digital to analog converter 30 converts the digital signal from summary means 28 to a single, analog, audio output signal, which signal may be amplified and used to drive a speaker (not shown in the figures).

Operation of the present invention may be understood more clearly in conjunction with FIG. 2a, which shows a typical complex wave shape 32 such as that which may be produced by an air driven organ pipe. As shown in FIG. 2a, typical wave shape 32 is sampled in amplitude at a plurality of sample points, equally spaced in time. The number of sample points used is not critical, however it has been found that 48 sample points per period (as shown in the illustration of FIG. 2a) is sufficient for excellent reproduction of a wave shape.

As shown in FIG. 2c, the amplitude of wave shape 32 at each of the 48 sample points may be represented by an eight bit binary word. Each eight bit word provides 128 amplitude levels as well as an algebraic sign bit. Use of such eight bit words to represent the amplitude of wave shape 32 permits the amplitude to be recorded digitally to an accuracy of better than one percent. Moreover the use of 48 sample points, together with use of an eight bit word to represent the wave shape amplitude at each of the 48 sample points theoretically permits replication of a wave shape containing a fundamental frequency and 23 harmonic overtones. This number of harmonics is adequate for excellent reproduction of any pipe organ voice, as well as for most other sustained musical instruments.

While wave shape 32 (see FIG. 2a) may be represented accurately in terms of amplitude at each sample point (as in the digital representation of FIG. 2c) it also is possible to represent the same wave shape in terms of amplitude increments. Such amplitude increment representation requires fewer bits, hence reducing the wave shape memory 24 storage capacity requirements. In FIG. 2b, the amplitude increments (i.e., differences) between successive sample points for wave shape 32 are shown at 33. Note that the spike 33a represents the difference between the amplitude of wave shape 32 at sample points 1 and 2. Similarly, the spike 33b represents the difference between the amplitude of wave shape 32 at sample times 2 and 3. FIG. 2d shows a possible binary representation of the amplitude increments of FIG. 2b. Wave shape memory 24 (see FIG. 1) contains the digital representation of wave shape 32, either in the amplitude form of FIG. 2c or, preferably, in the amplitude increment form of FIG. 2d. One such digital representation of a particular wave shape is used for producing all of the notes of the scale for a desired organ voice. Wave shape memory 24 however may contain the digital representations of several of different wave shapes, each being characteristic of a different rank of organ pipes. As noted earlier, stop tabs 25 are used to select which of the digital wave shape representations is read out, i.e., to select which rank of organ pipes is to be simulated with the inventive electronic organ.

The actual shape of the wave to be stored digitally in wave shape memory 24 may be determined by recording an actual air driven pipe organ sound and electronically measuring the wave shape amplitude at the sample points.

Since the stored digital representation of a single wave shape 32 is used for production of each note in the electronic organ scale, the frequency of the original recorded tone is of no consequence. Hence, in selecting the refer-

ence wave shape it is possible to examine a rank of organ pipes and select the one which has the best representative sound for that rank, irrespective of its particular note. The reference wave shape then is standardized to a normalized frequency by the 48 samples per period condition.

Referring now to FIG. 3 there is shown preferred embodiment of frequency synthesizer 10 (see FIG. 1). As evident in FIG. 3, oscillator 35 produces an output signal f_1 equal to N times the frequency of the highest note (here C_8) to be produced by the organ. As noted earlier, N equals the number of sample points in wave shape 32. Thus in the suggested implementation illustrated in FIG. 2, where wave shape 32 is represented at 48 sample points, $N=48$. Since the frequency of C_8 is 4186.01 Hz., the output frequency of oscillator 35 is $f_1=NC_8=48 \times 4186.01$ Hz. = 200928.48 Hz. Note that oscillator 35 may be a crystal oscillator, or may utilize some form of frequency standardization other than a piezoelectric crystal.

Referring still to FIG. 3, note that the output from oscillator 35 is supplied to divider 36a, the first of a series of scale of two dividers 36a, 36b . . . 36g, each of which divides by two the output from the preceding divider. Thus the output of scale of two divider 36a is at frequency $NC_8/2=NC_7$. Similarly, the output from divider 36b is at frequency $NC_7/2=NC_6$, while the output from scale of two divider 36g is $NC_2/2=C_1$. (Of course, N represents the integer corresponding to the number of sample points of stored wave shape 32.)

Each of the outputs from oscillator 35 and from dividers 36a, 36b . . . 36g provides an input to respective ones of gates 37a, 37b . . . 37h (see FIG. 3). A second input to each of gates 37 is provided by the keyboard switch from the corresponding organ manual or pedal key. Thus, for example, gate 37a receives a gating input (C_8) from the keyboard switch associated with the C_8 key on the organ manual. Similarly, gate 37h receives an input from scale of two divider 36g at a frequency NC_8 and a gating input (C_1) from the keyboard switch associated with the manual key C_1 . Clearly, the output from typical gate 37a is a clock signal at frequency NC_8 , gated on and off by depression of key C_8 . Note that the output of gate 37a, corresponds to line 16 in FIG. 1, while the output of gate 37h corresponds to line 14 of frequency synthesizer 10 (see FIG. 1).

The ratio of any two contiguous frequencies in an equally tempered musical scale is $2^{1/12}$. This is an irrational number, implying that any scheme to synthesize the equally tempered musical scale at best can yield only an approximation of the true frequencies. Derivation by frequency synthesizer 10 of the frequencies corresponding to notes other than C is based on the observation that $2^{1/12} = 196/185$. The error in this approximation is about 4×10^{-6} . This error will accumulate systematically throughout the generation of one octave, but will still be about 5×10^{-5} within an octave. This error is more than acceptable and certainly is better than the average organ or piano tuner can accomplish.

Referring again to FIG. 3, note that free-running multivibrator 39 is designed to have a frequency of approximately NB_7 . If multivibrator 39 is running at exactly the desired frequency $f_2=NB_7$, its output will be related to the output of oscillator 35 by the equality $f_1/f_2=196/185$. To ensure that multivibrator 39 is running at exactly the desired frequency NB_7 , the following scheme is used. First the output from oscillator 35 is fed to divider circuit 40 which divides the output of oscillator 35 by 196. Similarly, the output of multivibrator 39 at f_2 is fed to circuit 41 which divides f_2 by 185.

Circuits 40 and 41 respectively provide two inputs at frequencies $f_1/196$ and $f_2/185$ to frequency comparator circuit 42. If multivibrator 39 is running at exactly the correct frequency ($f_2=NB_7$) to produce the key of B_7 , then the two inputs to frequency comparator circuit 42

(i.e., $f_1/196$ and $f_2/185$) each will be at exactly the same frequency and no error signal will be present at the output of frequency comparator circuit 42. However, should multivibrator 39 be running at a slightly incorrect frequency, $f_2/185$ will not exactly equal $f_1/196$, and frequency comparator circuit 42 will produce an error signal. This error signal from circuit 42 then is fed back to multivibrator 39 appropriately to speed up or slow down the operating rate of multivibrator 39. This error signal thus insures that multivibrator 39 produces an output signal which is at exactly the desired frequency

$$f_2 = NB_7 = (NC_8/196) \times 185$$

The output f_2 from multivibrator 39 then serves as the frequency standard for the key of B for each octave of the inventive digital electronic organ.

The output of multivibrator 39 at frequency NB_7 is fed to a second set of scale of two dividers 43a, 43b . . . 43f which in a manner analogous to dividers 36a, 36b . . . 36g, divide the output frequency $f_2 = NB_7$ from multivibrator 39 successively by two. Dividers 43a, 43b . . . 43f provide outputs at frequencies NB_6 , NB_5 . . . NB_1 which respectively are supplied to gates 44b . . . 44h. Gate 44c receives an input clock signal at NB_7 directly from multivibrator 39. Each of gates 44a, 44b . . . 44h also receives a gating input from the keyboard switches, designated (B₇), (B₆) . . . (B₁), respectively. Thus, typically, if the manual key of B₆ is depressed, gate 44b will receive a gating input (B₆) from the keyboard switch, which will gate the clock signal at NB_6 from scale of two divider 43a to provide an output at frequency NB_6 .

The same divide and compare scheme is iterated through each of the twelve tones to obtain frequencies $f_3 = NA_{\#7} . . . f_{12} = NC_{\#7}$. For example, (referring still to FIG. 3), the output of multivibrator 45 at frequency $f_3 = NA_{\#7}$ is divided by 185 in divide circuit 46 to provide one input to frequency comparator circuit 47. The second input to frequency comparator circuit 47, at frequency $f_2/196$, is provided by divide circuit 48 which received its input from multivibrator 39. The error signal from frequency comparator circuit 47 insures that multivibrator 45 is producing an output at exactly the desired frequency $f_3 = NA_{\#7}$.

The output of multivibrator 45 at f_3 is divided by 196 in division circuit 49 (see FIG. 3) and supplied as an input to the frequency comparator circuit associated with the multivibrator (not shown) for frequency $f_4 = NA_7$. The iteration is continued through multivibrator 50 which supplies an output at $f_{12} = NC_{\#7}$, which output is divided by 185 in division circuit 51 and compared with $f_{11}/196$ in frequency comparator circuit 52. As before, circuit 52 provides an error signal to insure multivibrator 50 is operating at the correct frequency.

The circuitry for typical frequency comparator circuit 42 and for typical multivibrator 39 are well known to those skilled in the art. For example, these circuits may be implemented in a manner analogous to the early and late gate range tracking circuits used in radar systems.

Referring again to FIG. 3, the outputs at f_3 and f_{12} from multivibrators 45 and 50, and similarly the outputs at f_4 , $f_5 . . . f_{11}$ from multivibrators not shown in FIG. 3, each are divided by corresponding sets of scales of two dividers to provide clock signal outputs corresponding to notes $NA_{\#6}$, $NA_{\#5} . . . NC_{\#2}$, $NC_{\#1}$. For example, the output f_3 from multivibrator 45 is fed through scale of two dividers 53a, 53b . . . 53f to produce respectively clock signals at frequencies $NA_{\#6}$ through $NA_{\#1}$. The clock signals at $NA_{\#7}$ through $NA_{\#1}$ are sent to gates 54a, 54b . . . 54g, each of which receives a gating signal from respective ones of keyboard switches (A₇), (A₆) . . . (A₁). Thus, the output of gates 54a, 54b . . . 54g contain the keyed clock signals at frequencies $NA_{\#7}$, $NA_{\#6} . . . NA_{\#1}$. Similarly, clock signals at frequencies $NC_{\#7}$, $NC_{\#6} . . . NC_{\#1}$, keyed by inputs (C₇), (C₆) . . . 75

(C₁) from the keyboard switches, are provided by gating the outputs of multivibrator 50 and scale of two dividers 55a, 55b . . . 55f in gates 56a, 56b . . . 56g.

Production of musical tones using the inventive digital electronic organ further may be understood in conjunction with FIG. 4 which shows a preferred embodiment of wave shape memory 24 and recycling read control units 22a, 22b . . . 22n (see FIG. 1). Note in FIG. 4 that fixed diode array 60 is used to store digital representation of the amplitude increments of an organ wave shape (see e.g., wave shape 32 and its digital representation in FIGS. 2a and 2c respectively). Diode array 60 may be of the type described in the U.S. Pat. No. 3,377,513 to Ashby et al., assigned to North American Rockwell Corporation, owner of the present application. Diode array 60 comprises a microelectronic integrated circuit wherein a large number of diodes are arranged in a matrix of columns and rows on a single microelectronic chip.

For storage of a wave shape sampled at 48 points, diode array 60 (see FIG. 4) may have 48 rows of diodes, each now containing a digital word representative of the wave shape amplitude or incremental amplitude at corresponding ones of the sample points (e.g., see FIGS. 2a-2c). The number of columns used in diode array corresponds to the number of bits in each word of the digital representation stored. Thus in FIG. 4, diode array 60 comprises 48 rows, e.g. rows 61, 62, 63, 64, 65 and 66, in each of which is stored the digital words representing the wave shape amplitude or amplitude increments at sample times 1, 2, 3, 4 . . . 47, 48. Note that for each stored wave shape, such as that corresponding to an 8' diapason sound, six columns 67a, 67b . . . 67f are included in diode array 60. This permits storage of 6 bit amplitude increment words. Of course, words of other length (e.g., 8 bit amplitude words) also could be used by providing the appropriate number of columns in array 60.

A binary 0 is stored at a matrix intersection of diode array 60 (see FIG. 4) where there is no diode, while a binary 1 is stored at a row and column intersection at which there is a diode. Thus, in the example illustrated in FIG. 4, the amplitude increment word corresponding to sample point 1 is represented at the matrix intersections of row 61 with columns 67a, 67b . . . 67f. There are no diode at any of these intersections, hence, the digital word stored in column 61 is 000000. Note in row 62 that diodes 68 are located at the intersections with columns 67b, 67c and 67e. Thus the digital word stored in this second sample point position is 011010.

A single diode array 60 (see FIG. 4) may have many columns which are divided into groups, each group of columns containing a digital representation of a different wave shape. Thus each group of memory storage locations may correspond to a different organ stop. In the example illustrated in FIG. 4, diode array 60 has 12 columns, and is divided into two groups of six columns each. The six columns 67a, 67b . . . 67f represent, in the example, a wave shape characteristic of an 8' diapason voice, while the six columns 69a, 69b . . . 69f store the digital representation of a wave shape characteristic of 8' flute.

When a particular organ manual or pedal key is depressed, a clock frequency is produced by frequency synthesizer 10 (see FIGS. 1 and 3) having a frequency Nf , where N is the number of wave shape sample points stored in memory 24 (e.g., $N=48$ for diode array 60 of FIG. 4), and f is the characteristic frequency of the musical note selected. For example, if the key of C₁ is depressed, frequency synthesizer 10 will produce an output on line 13 at frequency $NC_1 = 48 C_1$. Referring to FIG. 1, read control assigner 20 will connect the clock signal at frequency $48 C_1$ to a presently unused one of recycling read control units 22a, 22b . . . 22n.

In the embodiment shown in FIG. 4, each recycling

read control 22 comprises a ring counter 70a, 70b . . . 70n. Each ring counter 70 is designed to advance its count by one for each input clock pulse, and when it reaches its maximum count, to start counting again from 1. Moreover, each counter 70 has a maximum count of N equal to the number of sample points in the stored wave shape. Thus, in the example of FIG. 4, each ring counter 70 counts to 48, and then resets and counts again from 1, for as long as an input clock signal is provided.

By way of example, suppose that when key C₁ is depressed, ring counter 70a (see FIG. 4) is available. Read control assigner 20 will direct the clock signal at frequency 48 C₁ from line 13 of frequency synthesizer 10 to the input of 48 ring counter 70a. This will cause ring counter 70a to produce successive outputs to rows 61, 62 . . . 65, 66 at a rate identical to the clock frequency 48 C₁. When ring counter 70a produces an output on a particular row (e.g., row 62) of diode matrix 60, outputs simultaneously are obtained on all columns 67a, 67b . . . 67f (as well as columns 69a, 69b . . . 69f) which are connected by diodes 68 or 68' to the selected row. Thus columns 67a, 67b . . . 67f will contain successively 6 bit parallel signals corresponding to the digital words stored in successive rows of diode array 60. These output words will occur at a rate of 48 C₁ words per second, and since there are 48 words, and they are accessed repetitiously by ring counter 70a, the entire set of 48 words will appear repetitiously as outputs on columns 67a, 67b . . . 67f at the rate C₁.

As mentioned, accessing of diode array 60 (see FIG. 4) by ring counter 70a will produce outputs on lines 67a . . . 67f, and also on lines 69a . . . 69f. Selection of which of these sets of outputs is to be accepted by attack and decay control circuitry 26 (see FIG. 1) is determined by the setting of the stop tabs 25. Thus, if the 8' diapason stop tab is selected, gate 71 (see FIG. 4) will be ON while gate 72, associated with the 8' flute stop tab, will be OFF. Alternatively, of course, output from the 8' flute columns 69a, 69b . . . 69f, of diode array 60 may be obtained by selecting the 8' flute stop tab, thereby gating signals through gate 72.

With the 8' diapason stop selected, the output of gate 71 in time comprises repeated sets of 48 six bit words, each word representing the amplitude increment of the stored 8' diapason wave shape at one of the 48 sample points. The set of 48 words continues repetitiously for as long as an input is provided (in the example) to 48 ring counter 70a. The rate at which the words appear at the output of gate 71 is 48 C₁, i.e., one complete wave shape or period is read out at selected frequency C₁. Alternatively expressed, a digital representation of a musical note at frequency C₁ is present at the output of gate 71. The digital representation, of course, corresponds to a wave shape having the characteristics stored in the diode array (e.g., an 8' diapason) reproduced at a rate corresponding to the note selected on the organ manual or pedal keyboard. Note that the outputs from gate 71 are available at the inputs to each of gates 75a, 75b . . . 75n, which gates serve the function of directing each data word to the particular attack and decay control circuit associated with the note being keyed. This is important when a chord is played on the organ, as for example, when the keys C₁ and B₁ are struck simultaneously.

When (C₁) and (B₁) inputs are obtained at the same time, frequency synthesizer 10 produces outputs at 48 C₁ and at 48 B₁ (assuming N=48). Read control assigner 20 may direct clock signal 48 C₁ to ring counter 70a (see FIG. 4) while clock signal 48 B₁ may be directed to ring counter 70b. In this instance, ring counter 70a and 70b both will be accessing diode memory 60. Ring counter 70a will be producing outputs on successive rows by the same clock signal (designated 48 f_a) which also 61, 62 . . . 66 at a faster rate than will ring counter 70b. Each time a data word is accessed by ring counter 70a, gate 75a (see FIG. 4) simultaneously is activated

is being fed to ring counter 70a. Thus, each word read by ring counter 70a will be gated via gate 75a to the attack and decay control circuitry associated with ring counter 70a.

Similarly, each time ring counter 70b accesses a word from diode array 60, this word is gated through gate 75b, which gate also receives the clock signal 48 f_b being fed to ring counter 70b. Thus, the particular data words from wave shape memory 10 associated with each note simultaneously being played appear at the outputs of separate gates. In the example, the output of gate 75a contains only words associated with C₁ while the output of gate 75b contains only words associated with B₁.

Note that the outputs of gates 75a, 75b . . . 75n may be fed directly to summing means 28 (see FIG. 1) thereby omitting the shaping accomplished in attack and decay control circuitry 26. Under these conditions, the operation of summing means 28 may be understood in conjunction with FIGS. 5a, 5b and 5c.

In the example discussed hereinabove, the two keys C₁ and B₁ were struck simultaneously thereby producing outputs from gates 75a and 75b, each of which may be fed directly to summing means 28. In this case, a portion of signals entering summing means 28 are illustrated in FIGS. 5a and 5b. Note in FIG. 5a that the typical output from gate 75a comprises a set of digital words (which are shown for simplicity as 4 bit words, but which of course may be 6-bit, 7-bit, etc.) corresponding to the words stored in consecutive rows of diode array 60. The words are read out at the clock rate 48 C₁, the rate at which ring counter 70a is accessing diode array 60. The output of gate 75b (see FIG. 5b) contains a like set of words read out from diode array 60 by ring counter 70b at the clock rate 48 B₁.

Summing means 28 operates in the following manner. Initially, it is set to zero. Then, each successive input received from any of gates 75a, 75b . . . 75n (either directly, or via attack and decay circuitry 26) is added to the preceding total and held till the next input arrives. Thus, in the example of FIG. 5c, the first non-zero increment to arrive at summing means 28 is binary 1001 from gate 75b; this is added to zero and the sum (1001) is stored.

When the next amplitude increment word (in the example of FIG. 5a binary 1100 from gate 75a) arrives at summing means 28, this increment is added to the sum (1001) presently stored therein to yield a new sum of 1101. The next increment (1001 from gate 75a) in turn is added to the sum (1101) stored in summing means 28 to derive the new sum 1110. This operation continues progressively.

The sum stored in digital form in summing means 28 is converted to an analog waveform by digital to analog converter 30 (see FIG. 1). In the example of FIG. 5, the analog output from digital to analog converter 30 would have the appearance illustrated in FIG. 5d, and corresponding to the digital sum of FIG. 5c. The analog wave shape produced by converter 30 will correspond to the sum of the wave shapes being read out of diode array 60 as one or more keys are struck. Of course, if only one key is depressed, summing means 28 will receive only one input, and the output of digital to analog converter 30 will correspond to the single selected note.

Storage of amplitude increments in diode array 60 facilitates simplified summation and analog conversion in summing means 28 and converter 30 respectively. Of course, an amplitude representation also could be employed. Moreover, while the example of FIG. 5 shows only 4 bits being used to define the wave shape amplitude increments, use of other numbers of bits is envisioned within the scope of the present invention.

The typical output from digital to analog converter 30 shown in FIG. 5d is a step function. However, the sample points for each note produced are closely spaced in time, hence, the analog signal produced sounds to a

listener as a normal audio signal, with remarkable resemblance to an air driven pipe organ. Since the analog signal is a step function, output of digital to analog converter 30 will contain high frequency components associated with the abrupt steps. These high frequency components may be filtered out by use of a low pass filter typically having a cutoff frequency below 20,000 Hz.

Alternatively, there is no necessity to provide such low pass filtering. In fact, the high frequency components present in the step function produce a sound similar to the air sound or hiss produced by an air driven organ pipe and conventionally simulated in an electronic organ by using a white noise generator.

To simulate most accurately a true pipe organ sound, it is important that each note produced be shaped to have a non-abrupt rise and fall time. Referring to FIG. 6, there is shown a generalized graph of the amplitude versus time characteristics of a single note played on a pipe organ. Typically, the note is divided into three sections, called respectively, attack, sustain, and decay. During the attack or initial portion of the note the amplitude of the note increases to its maximum value at time t_1 . Typically, t_1 corresponds to a period of between 10 and 100 milliseconds over a rank of 8' organ pipes. The following Table I indicates that if the attack lasts for about seven periods of the fundamental frequency of the note, the proper range for t_1 is obtained.

TABLE I

Note	Frequency (in Hz.)	Period (in milliseconds)	7 periods (in milliseconds)
C ₁ -----	32.70	30.58	214.06
C ₂ -----	65.41	15.290	157.03
C ₃ -----	130.81	7.695	78.51
C ₄ -----	261.63	3.848	39.26
C ₅ -----	523.25	1.924	19.63
C ₆ -----	1046.50	0.962	9.82
C ₇ -----	2093.00	0.481	4.91
C ₈ -----	4186.01	0.241	2.46

Referring still to FIG. 6, when the maximum amplitude has been reached, the note is sustained at approximately constant amplitude for as long as the key is depressed. This period, between times t_1 and t_2 , is designated "sustain." Finally, when the key is released, the note being sounded does not stop abruptly, but decays logarithmically, dying out at time t_3 . The "decay" period also corresponds approximately to seven periods of the fundamental frequency.

The amplitude shape of FIG. 6 is related to each individual note played. When two or more organ keys are struck simultaneously, each note generated independently preferably should resemble in amplitude the characteristics of FIG. 6. It is for this reason that independent attack and decay control circuits are desirable for each of gates 75a, 75b . . . 75n (see FIG. 4), the outputs of which each correspond to a single selected note. The manner in which attack and decay amplitude effects may be implemented digitally is described below.

Referring to FIG. 7, it is seen that logarithmic decay curve 80 may be simulated as a step function over a duration of seven periods τ of the fundamental of the note being sounded. In FIG. 7, the amplitude during the first period after t_2 (see FIG. 6) is represented by $A/2$, where A is the amplitude during the sustain period. During the second period, the amplitude is $A/4$, during the third period, it is $A/8$, etc. Such a wave amplitude step function readily can be accomplished digitally since division of a binary number is accomplished by shifting the number to the right. A shift of one position corresponds to division by 2, a shift of two positions accomplishes division by 4, three positions divides by 8, etc.

To implement the logarithmic decay represented in FIG. 7 first requires that the clock signal generated by frequency synthesizer 10 extend in duration beyond the release of the associated keyboard switch. Referring to FIG. 8 there is shown one possible implementation of

a circuit to provide this function. As shown in FIG. 8, typical gate 37h' corresponds to gate 37h (in FIG. 3) and receives a clock signal at frequency NC_1 from divider 36g. Gate 37h' also receives an input from keyboard switch (C₁) via OR gate 82. Thus, as in the embodiment of FIG. 3, gate 37h' is gated ON during the time key (C₁) is depressed.

The signal (C₁) also is differentiated by capacitor 83 and resistor 84 (see FIG. 8) to provide a positive going transient when (C₁) begins, and a negative going transient when (C₁) ends. Diode 85 bypasses the positive going transient to ground, so that the input 87 to one shot multivibrator 86 is a negative going pulse 87' which occurs when the key (C₁) is released.

One shot multivibrator 86 preferably is selected to have an ON time which is equal to or greater than 7 periods of the note (in this case C₁) being played. Thus, the output of one shot 86 is a square wave, designated (END) and shown in the graph of FIG. 8. Note that this (END) signal also provides an input to OR gate 82, thereby maintaining gate 37h' ON following the release of key (C₁) for a time greater than or equal to seven periods at the frequency of note C₁. Thus the circuit shown in FIG. 8 (or other equivalent circuit) ensures that an output at the synthesized frequency NC_1 is provided for a duration equal to the time (C₁) is depressed, plus an additional period sufficiently long to enable attack and decay control circuitry 26 (see FIG. 1) to provide a shaped decay rather than an abrupt termination to the note.

Implementation of the decay waveform shown in FIG. 7 is facilitated by the attack/decay circuit shown in FIG. 9. In a preferred embodiment of the invention, circuit such as that shown in FIG. 9 is associated with the output of each gate 75a, 75b . . . 75n (see FIG. 4). Referring to FIG. 9, digital words read from diode array 60 (see FIG. 4), in 6 bit parallel form, are fed from typical gates 75a to shift register 90. (In FIG. 9, use of the numeral 6 in a circle indicates that data is in 6-bit parallel form.)

Shift register 90 (see FIG. 9) is controlled by shift control 91 which, in a manner well known to those skilled in the art, controls the number of positions to the right shift register 90 will shift each incoming word from gate 75a. In the particular embodiment shown in FIG. 9, shift control 91 directs shift register 90 to shift each incoming word from gate 75a to the right, the number of places shifted corresponding to the output of counter 92. Thus if counter 92 is producing a count of one, shift control 91 will cause shift register 90 to shift each word received from gate 75a one position to the right. Each shifted word then is fed out, in parallel, from shift register 90 to gate 93.

To accomplish the decay function, counter 92 is caused to begin counting when the (END) pulse, associated with the note being played and generated in a circuit such as that of FIG. 8, appears as an input to start count circuit 95. Start count circuit 95, when triggered by (END) sets counter 92 to one, and initiates counting by counter 92. Counter 92 then advances each time an f_a pulse is received. Referring to FIG. 4, it will be seen that the f_a pulse is derived from position 48 on ring counter 70a. Thus, counter 92 will advance once for each complete wave shape (comprising 48 data words) read from diode array 60 via gate 75a. Recalling that these 48 words comprise one complete period of the musical note being generated, it is evident that counter 92 advances by a count of one for each complete period of the note.

As an example, if the key (C₁) is struck (and read control assigner 20 has assigned the output of gate 37h' (see FIG. 8), at frequency NC_1 , to ring counter 70a), when key (C₁) is released, the (END) pulse will occur. This (END) pulse will energize start count circuit 95 (see FIG. 9) and hence begin counting by counter 92.

For the first period of the note C after (END), i.e., for the first 48 words thereafter read from diode array 60,

a shift of one position to the right will occur in shift register 90, as counter 92 will be set at its one position. As shifting of a digital word one position to the right corresponds with division by two, each of these first 48 words will represent an amplitude increment having one-half the value represented by the unshifted digital word. Thus, the effective amplitude of the resultant analog note produced will have an amplitude, between time t_2 and $t_2+\tau$ of $A/2$, where A is the sustain amplitude of the note (see FIG. 7). At time $t_2+\tau$ ring counter 70a will reach its 48th position, f_a will appear, and counter 92 will advance to count two. Shift control 91 then will cause shift register 90 to shift each incoming word from gate 75a two positions to the right. This right shift of two positions corresponds to a division by 4. Hence, for the succeeding 48 words, i.e., for the succeeding one period of the key of C_1 , the effective amplitude produced will be $A/4$, as indicated again in FIG. 7. This procedure will be carried out during successive readouts of diode array 60 until at period 7τ the shift will be 7 positions, a division by 128. Clearly the amplitude at this time will be essentially zero. Note at time 8τ shift control 91 will turn OFF, since the DEC pulse provided to shift control terminates at the end of the count of 7 (see the truth table of FIG. 9). The DEC signal is provided by logic circuitry (not shown) well known to those skilled in the art which is responsive to the clock signal at frequency Nf_a , the true (END) signal, and a count of ≤ 7 from counter 92 after (END).

During the decay period, gate 93 is gated ON by the DEC pulse. Thus data words from shift register 90 will appear at the output of OR gate 96 and will be available at the input to summing means 28.

Note that counter 92 may be of any desired length, nor is it required that shift register 90 be programmed to shift by a constant number of positions for each period of the note being produced. Thus, if a faster decay is desired, shift control 91 and counter 92 could be adapted so that counter 92 advances by two, three or other value per each period. (This can be accomplished by keying counter 92 with appropriate outputs from ring counter 70a.) Similarly, a slower decay can be obtained by advancing counter 92 each second, third, or fourth occurrence of f_a . Of course, appropriate programmatic controls may be provided to allow the particular decay characteristics to be selected either by operator intervention or by a stored or selectable programming means.

Referring to FIG. 10, there is shown a graph indicating how the attack portion of a note (see FIG. 6) also may be implemented digitally. In FIG. 10 it may be seen that an exponential increase in amplitude is simulated by a step function where in each step is of time τ equal to a period of the note being produced. The initial step is to amplitude

$$A - \frac{A}{2}$$

the next step to amplitude

$$A - \frac{A}{4}$$

the next step to

$$A - \frac{A}{8}$$

and so forth. This attack waveform can be implemented digitally using a simple scheme of shifting and subtracting.

Referring again to FIG. 9, recall that the attack wave-shaping should start as soon as a key is depressed. In the example, when key (C_1) is pressed down, the initial occurrence of $Nf_a = NC_1$ (that is, the initial occurrence of the output clock pulse from gate 37h' (in FIG. 8) is sensed by appropriate logic (not shown) which provides an attack gating pulse ATT. As shown by the truth table in FIG. 9, ATT occurs when Nf_a (in this case 48 C_1) is

true, when counter 92 has counted ≤ 7 after Nf_a , and when the (END) pulse is false. That is, the ATT pulse is initiated as soon as a key is depressed.

Occurrence of the ATT pulse activates shift control 91 which, as before, causes shift register 90 to shift to the right each word received from gate 75a by a number of places equal to the counter of counter 92. Again, counter 92 is advanced (in the embodiment shown) by the signal f_a derived from position 48 of ring counter 70a. The occurrence of Nf_a causes circuit 95 to start counter 92 at a count of zero. The ATT pulse also gates the shifted output from shift register 90 via gate 97 to subtract circuit 98. Subtract circuit 98 also receives each unshifted word directly from gate 75a. The output of subtract circuit 98 is a digital word representing the difference between the unshifted word directly from gate 75a and the word from gate 75a shifted by shift register 90. This binary difference value is gated through gate 99 (which also receives an ATT pulse) to OR gate 96.

Note that as soon as a key is depressed, the first 48 words read from diode array 60 will not be shifted by shift register 90 since counter 92 initially is set to zero by Nf_a . Since the unshifted word, as gated through gate 97, will be subtracted from the unshifted word received

directly from gate 75a in subtract circuit 98, the output to gate 99 during the first period of the note being produced will be zero. This is illustrated in FIG. 10 during the period between zero and τ . At time τ , ring counter 70a will have reached its 48th position, generating an f_a pulse which advances counter 92 to its one position.

During the subsequent readout of 48 words from diode array 60, that is, during the second period of the note being generated, each word read into shift register 90 will be shifted to the right one position. Since shifting to the

right one position is the equivalent of dividing by 2, subtract circuit 90 (during the time τ to 2τ as shown in FIG. 10) will receive directly from gate 75a an unshifted signal and from shift register 90a a signal having its value divided by 2. Thus, the output at gate 99 will be a set of

digital words representing amplitude increments which have half the value of those stored in diode array 60. Similarly, on the period 2τ to 3τ , counter 92 will be set at 2, causing shift register 90 to shift each incoming word two positions to the right. Thus, subtract circuit 98 will subtract from an unshifted signal received from gate 75a a signal having one-quarter value. Thus the resultant amplitude will be

$$A - \frac{A}{4} = .75A$$

(see FIG. 10). Successive steps produce a waveshape as that shown in FIG. 10. Note that after counter 92 has reached 7 the ATT pulse will end, and the end of the attack cycle will have been reached.

With the end of the attack cycle, the sustain pulse SUS (see the truth table of FIG. 9) will be true. In this case, shift control circuit 91 will be OFF, since it is not receiving either an ATT or a DEC pulse. Likewise, gates 97 and 99 each will be OFF. Thus, each data word from gate 75 will enter shift register 90, will not be shifted, and will be read out unshifted via gate 93 (activated by the SUS pulse) to OR gate 96 and thence to summing means 28.

As in the decay case, while the example has been presented in terms of a logarithmic attack, the invention is not so limited. By appropriately programming shift control circuit 91 and counter 92 other attack wave shapes can be generated. For example, the wave shape shown in FIG. 11 could be generated by programming combinations of shift, and shift and subtract operations. The wave shape of FIG. 11 well may be of value in simulating instruments having percussive qualities (e.g., a bell). As in the case of the decay, the selected attack may be controlled by preprogrammed logic or, by means of a stored program, selection switches operated by the

performer, or even by punched card containing a particular attack/decay scheme encoded thereon.

Although described hereinabove in terms of utilization of a fixed diode array for wave shape memory 24, the invention clearly is not so limited, and any type of digital memory may be used. For example, wave shape memory 24 may comprise a standard magnetic core memory well known in the computer art. In such instance, recycling read control circuits 22a, 22b . . . 22n each may comprise a ring counter (driven by the clock signal from frequency synthesizer 10) and appropriate read and write circuitry for reading out the state of magnetization of each core and or rewriting the data back into each core (required since such memories have destructive readout). Alternatively, plated wire or thin film memories could be used for wave shape memory 24.

Moreover, while the operation of wave shape memory 24 has been described hereinabove in terms of a parallel readout, this is not required by the invention, and serial readout also may be employed. Recall that the amplitude or amplitude increment digital words stored in memory 24 are read out at a rate which is N times the frequency of the note being produced, wherein is N the number of sample points utilized. Typically, the highest note produced is C₈ at 4186.01 Hz. Thus, the maximum rate at which successive sample points are sampled is on the order of 50 milliseconds (for 48 sample points per period). Clearly, 50 milliseconds is sufficient time to permit serial readout of the 6 or 8 bits typically used to represent the wave shape amplitude or amplitude increment at each sample point.

Serial readout may be used either with a diode array or with any other type of digital storage device utilized for wave shaped memory 24. For example, referring to FIG. 4, while each output of the ring counters 70a, 70b . . . 70n is shown connected directly to a row of diode arrays 60, these connections could be made via gates. Then instead of the six columns 67a, 67b . . . 67f going directly to gate 71, appropriate circuitry could be provided to scan these columns 67a, 67b . . . 67f one at a time to provide a serial input to gate 71. Thus, e.g., when ring counter 70a reaches a count of 2, row 62 of diode array 60 would be energized via a gate. Columns 67a, 67b . . . 67f then would be scanned, one at a time, at a sufficiently high rate so that all six columns are scanned prior to the advance of ring counter 70a to a count of three. The serially scanned output from diode array 60 then may be entered into a 6 bit register (not shown) and this register used to provide a parallel output to the remainder of the digital electronic organ circuitry. With this column scanning techniques, the gates between each ring counter 70a, 70b . . . 70n and the rows 61, 62 . . . 66 of diode array 60 can be activated with appropriate time relationship to ensure, if desired, that more than one row of diode array 60 is not accessed, simultaneously.

Another feature of the inventive digital electronic organ is that the effect of intra-manual coupling of keys can be accomplished without the prior art requirement for mechanical or electrical coupling between sets of keys. For example, suppose that a flute stop is being used, but that a 4' voice rather than an 8' voice is desired. In this case, when C₃ is keyed, the organ must sound C₄ (i.e., $2 \times C_3$) with the same or similar flute voice as used for the 8' flute. Large pipe organs accomplish this action by having a separate rank of pipes for the 4' stops, which are distinct from any of the 8' ranks. The inventive digital electronic organ can readily duplicate this function.

Shown in FIG. 12 is a simplified diagram of a memory organization for wave shape memory 24 useful for effectuating harmonic and mutation stops. In storage area 101 there is stored the 48 words digitally representing one period of the wave shape of a particular rank of 8' pipes (e.g., 8' flute). These words are exactly analogous to

those shown in FIGS. 2c and 2d for the typical wave shape of 32 of FIG. 2a. As described hereinabove, when this one period of 48 words is accessed at a rate 48 times that of the note selected, the signal produced will represent a note at the selected frequency.

Suppose that for the same wave shape (i.e., flute) a 4' voice is desired. By reading out the two periods of the wave shape stored (as two blocks of 24 words) in storage area 102 (see FIG. 12) at the same rate as that at which the single period of storage area 101 normally is read out, the resultant note will be at twice the frequency of the key played. For example, if C₃ is struck while a 4' stop tab is selected, the output of frequency synthesizer 10 will produce a clock frequency at rate NC₃. When this is used to read out column 102 (which in 48 words are used to store two periods of the same wave shape), the output frequency produced will be at $(2 \times C_3) = C_4$. For realism the wave shape for the 4' stop (i.e., the wave shape two periods of which are stored in area 102) can be made to differ from the shape of the parent 8' stop stored in storage area 101.

In exactly the same fashion, 2' stops can be obtained by accessing storage area 103 (see FIG. 12). For a 2' stop, when key (C₃) is struck, the note which is sounded should be $(4 \times C_3) = C_5$. As seen in FIG. 12, storage area 103 contains four periods of the selected wave shape, each period represented by 12 words. Thus, when storage area 103 is accessed at the 8' rate 48 C₃, the wave shape produced is at the fourth harmonic (i.e., second octave). Similarly, a 1' stop is obtained when storage area 104, containing 8 periods each of 6 words, is read out with the basic 8' clock frequency. In this case, when key (C₃) is depressed, the note which will be produced will be (C₆).

While the harmonic stops accurately and easily can be obtained with the preceding scheme, it is slightly more difficult to obtain the mutation stops without intra-manual coupling. However, it is a feature of the present invention to provide apparatus for generating the mutation stops with sufficient listening accuracy and without couplers.

A 2 $\frac{2}{3}$ ' stop usually is obtained in an organ by electronically or mechanically coupling keys so that the representative action shown in Table II is obtained.

TABLE II

Note keyed on manual	Frequency (in Hz.)	Note sounded by organ	Frequency (in Hz.)
C ₄ -----	261.63	G ₅ -----	783.99
D ₄ -----	293.66	A ₅ -----	880.00
E ₄ -----	329.63	B ₅ -----	987.77
F# ₄ -----	369.99	C# ₆ -----	1,108.73
G# ₄ -----	415.30	D# ₆ -----	1,244.51
A# ₄ -----	466.16	F ₆ -----	1,396.92
C ₅ -----	523.25	G ₆ -----	1,567.98

A 2 $\frac{2}{3}$ ' pipe is roughly the third harmonic of an 8' pipe. The error between the true 2 $\frac{2}{3}$ ' coupled frequency and the third harmonic of the key note is exhibited in the following Table III which represents the error spread throughout the frequency range of the organ.

TABLE III

Note keyed on manual	Frequency (in Hz.)	Third Harmonic (in Hz.)	True 2 $\frac{2}{3}$ ' coupled frequency (in Hz.)	Error (in Hz.)
C ₁ -----	32.70	98.10	98.00	+.10
C ₂ -----	65.41	196.00	196.00	.23
C ₃ -----	130.81	392.43	392.00	.43
C ₄ -----	261.63	784.89	783.99	.90
C ₅ -----	523.25	1,569.75	1,567.98	1.77
C ₆ -----	1,046.50	3,139.50	3,135.96	3.54

The 2 $\frac{2}{3}$ stop usually is not used above C₅. Thus, it is seen that this stop can be obtained without coupling by using a memory storage scheme such as that represented by storage area 105 in FIG. 12. In storage area

105, three periods of the desired wave shape are stored, each in 16 words. When storage area 105 is read out at the 8' frequency (corresponding to 48 times the note keyed on the manual), the output obtained is the third harmonic. As may be seen from Table III above, this is a satisfactorily close approximation of the true 2 1/3' coupled frequency.

A more difficult problem arises in trying to obtain a 1 1/3' stop by means of harmonic generation without intra-manual couplers. This problem is illustrated in the following Table IV.

TABLE IV

Note Keyed on Manual	Frequency (in Hz.)	Fifth harmonic (in Hz.)	True 1 1/3' Note	Frequency (in Hz.)	Error in fifth harmonic approximation (in Hz.)
C ₁ -----	32.70	163.50	E ₃ -----	164.81	-1.31
C ₂ -----	65.41	327.05	E ₄ -----	329.63	-2.58
C ₃ -----	130.81	654.05	E ₅ -----	659.26	-5.21
C ₄ -----	261.63	1308.15	E ₆ -----	1318.51	-9.36
C ₅ -----	523.25	2616.25	E ₇ -----	2637.02	-20.77

It is evident that the fifth harmonic is an unacceptable approximation to the true 1 1/3' coupled stop. Another scheme for obtaining a better approximation is a feature of this invention. The ratio between a keyed note and its true 1 1/3' coupled note is

$$R=5.0397$$

That is, the error in using the fifth harmonic is about 4%.

Consider the storage allocation illustrated in FIG. 12 as storage area 106. Here 11 periods of a reference wave shape are stored in 105 memory addresses. If these words are read out at an 8' stop clock frequency, the ratio between the 8' frequency and that read from the 105 word register (storage area 106) is

$$R' = \frac{48}{105} \times 11 = 5.0286$$

Using this arrangement, the frequency error has been reduced to less than 3% of the fundamental. The following Table V illustrates the performance obtained by using storage area 106 of FIG. 12 to generate 1 1/3' stops without couplers.

TABLE V

Note keyed on manual	Frequency (in Hz.)	R' × frequency (in Hz.)	True 1 1/3' frequency (in Hz.)	Error (in Hz.)
C ₁ -----	32.70	164.44	164.81	-37
C ₂ -----	65.41	328.87	329.63	-74
C ₃ -----	130.81	657.74	659.26	-1.52
C ₄ -----	261.63	1315.48	1318.51	-3.03
C ₅ -----	523.25	2630.96	2637.02	-6.16

Implicit in the scheme for obtaining the 1 1/3' stops, is another feature of the invention. Prior art electronic organs have been limited to generating tones containing a mixture of a fundamental and harmonic overtones. The inventive digital electronic organ can use either harmonic or anharmonic overtones at the discretion of the designer. Anharmonic overtones are generated similar to the scheme shown as storage area 105 in FIG. 12.

Let N =number of words for an 8' stop (48 has been used to describe the operation in this disclosure)

W =Number of words in anharmonic wave shape memory

p =number of periods of reference wave shape stored in W .

Then,

$$R_a = \frac{N_p}{W}$$

where R_a is the ratio of the anharmonic frequency to the 8' clock signal selected by the manual keys.

The importance of being able to generate anharmonic overtones is especially vital to theatre organ design. Many of the percussive musical sounds are composed of anharmonic overtones. This is true of chimes, bells, struck bars, etc.

Although the invention has been described and illustrated in detail, it is to be clearly understood that the same is by way of illustration and example only and is not to be taken by way of limitation, the spirit and scope of this invention being limited only by the terms of the appended claims.

I claim:

1. In combination:

means for storing in digital representation a wave shape, and

means for repetitiously reading said wave shape at a selectable rate and producing therefrom a musical note.

2. The combination defined in claim 1 wherein the amplitude of said wave is digitally represented at a plurality of points.

3. The combination defined in claim 2 wherein said plurality is sufficiently great as to define a complex musical waveform.

4. The combination defined in claim 1 wherein said digital representation comprises a plurality of digital words, each word representing the incremental change in amplitude of said wave at successive ones of a like plurality of sample points.

5. The combination defined in claim 4 further comprising:

means for algebraically summing said read out digital words and for producing an audio signal corresponding in level to the value of the accumulated sum of the incremental changes in amplitude represented by said read out words.

6. The combination defined in claim 4 further comprising:

means for programmatically, algebraically modifying the incremental amplitude changes represented by selected read out digital words to control the amplitude characteristics of the musical note produced therefrom.

7. The combination defined in claim 1 wherein each word contains sufficient bits to define accurately an amplitude increment of a musical waveform.

8. The combination defined in claim 1 further comprising means for selecting said rate.

9. The combination defined in claim 1 further comprising:

means for simultaneously repetitiously reading said wave shape at a plurality of selectable rates and producing therefrom a musical chord.

10. An electronic organ comprising:

a memory containing a digital representation of wave shape,

read out means for repetitiously reading out said digital representation from said memory at a selectable rate, and

means for producing from said read out digital representation a musical note.

11. An electronic organ as defined in claim 10 further comprising:

a plurality of read out means for repetitively reading out said digital representation at a like plurality of individually selectable rates, and

scanning means for sequentially enabling readout of each word in said digital representation by each of said plurality of read out means.

12. An electronic organ as defined in claim 10 wherein a period of said wave shape is represented at N sample points, and wherein said rate is Nf , f being the frequency of said musical note.

13. An electronic organ as defined in claim 12 further comprising:

21

frequency synthesizer means for producing a clock signal at a frequency Nf in response to depression of a key of said organ, and wherein the reading rate of said read out means is determined by said clock signal.

14. An electronic organ as defined in claim 12 wherein said means for producing comprises:

summing means for digitally combining successive digital words read from said memory, said words representing said wave shape at successive sample points.

15. An electronic organ as defined in claim 4 wherein said means for producing further comprises:

digital to analog converter means for accepting said combined digital words and for producing an analog output representative thereof.

16. An electronic organ as defined in claim 15 wherein said means for producing further comprises:

speaker means for producing an audible signal in response to said analog output, and wherein said analog output comprises a step function having steps containing high frequency components which when reproduced by said speaker means simulate the hiss or air sound of a pipe organ.

17. An electronic organ as defined in claim 12 further comprising:

means for modifying said read out digital representation thereby to effectuate attack and decay of said musical note.

18. An electronic organ as defined in claim 14 further comprising:

means for programmatically right shifting said words read from said memory thereby effectuating decay of said musical note.

19. An electronic organ as defined in claim 14 further comprising:

means for programmatically shifting said words read from memory and for subtracting said shifted words from the same words unshifted, thereby effectuating attack of said musical note.

20. An electronic organ as defined in claim 10 wherein said memory contains a plurality of digital representations of a like plurality of wave shapes, and further comprising:

stop tab means for selecting which of said representations is to be read out repetitiously by said read out means.

21. An electronic organ as defined in claim 12 wherein said memory further contains a digital representation of m periods of wave shape, wherein $m=2, 4, 8$, and wherein in each of said m periods is represented by N/m sample points, and wherein said m periods are read out from said memory at said selectable rate Nf , thereby producing harmonic notes.

22. An electronic organ as defined in claim 10 wherein said memory further contains a digital representation of p periods of a wave shape, each period being represented by W words, and wherein said p periods are read out of said memory repetitiously at a rate $R_a Wf/p$, where R_a is the ratio of the frequency of the anharmonic note being produced and the frequency f of said musical note.

23. An electronic organ as defined in claim 10 wherein said memory comprises a diode array.

24. In combination:

a diode array containing a plurality of digital words stored in N rows of 1 columns, where 1 is the number of bits per word, said words comprising a digital representation of a wave shape sampled at N points, frequency synthesizer means for generating a clock signal at a rate Nf , where f is a selectable frequency,

ring counter means advanced by said clock signal for providing a voltage to successive rows of said array, means for summing the successive signals appearing on said 1 columns of said array as said voltage is pro-

22

vided, said successive signals corresponding to said words, and means for converting said summed successive signals to analog form.

25. In combination:

a memory in which is stored digital representations of a plurality of different wave forms, means for selecting which of said representations is to be read from said memory, and means for repetitiously reading said selected representation from said memory and for producing therefrom an analog signal having said selected wave form.

26. In combination:

first means providing a digital representation of a complex wave, and second means responsive to said first means for providing musical notes from said representation.

27. Means for storing sampled amplitudes of the complex wave of a musical note, means responsive to such stored sampled amplitudes for generating a musical note.

28. The combination recited in claim 27 wherein said responsive means comprises means for repetitiously reading said sampled amplitudes.

29. The combination recited in claim 27 wherein said responsive means comprises means for repetitiously reading said sampled amplitudes at one or more rates.

30. The combination recited in claim 27 wherein said means for storing comprises a digital memory.

31. The combination recited in claim 27 wherein said means for storing comprises a diode matrix.

32. An electronic organ comprising:

a memory containing a plurality of digital words representing amplitude information of a waveshape at a plurality of sample points;

a plurality of read out means simultaneously operable to repetitiously read out said memory at selectable rates;

control means operable in response to depression of a key of said organ for assigning a read out means to repetitiously read out said memory at a rate selected in accordance with the note corresponding to the depressed key, and means for producing from said read out digital words a musical note.

33. An electronic organ as recited in claim 32 wherein said control means comprises:

a frequency synthesizer including a master clock signal source and note identifying means responsive to each depressed key to generate a corresponding control clock signal, and

each of said assigned read out means is controlled to read out said memory at a rate determined by the corresponding control clock signal.

34. An electronic organ as recited in claim 32 where-

in:

said control means responds to simultaneously depressed keys for controlling each of the correspondingly assigned read out means to read out a single digital word individually, and for controlling said plurality of assigned read out means to simultaneously and repetitiously read out the plurality of digital words representing a waveshape contained in the memory at different rates selected in accordance with the notes corresponding to the depressed keys.

35. An electronic organ as recited in claim 32 wherein said memory includes group of plural digital words representing amplitude information of corresponding different waveshapes, and there is further provided:

a plurality of waveshape selecting gates, respectively associated with the outputs of said memory corresponding to said groups of digital words;

means connecting the outputs of said waveshape selecting gates to said note producing means, and means operable to selectively enable said gates for selecting the respectively associated groups of digital

words to be read out from said memory and applied to said producing means.

36. An electronic organ as recited in claim 35 wherein there is further provided:

a plurality of read out gates respectively associated with said plurality of read out means, said plurality of read out gates being connected at their inputs to the outputs of said waveshape selecting gates, and at their outputs of said note producing means, and each of said plurality of read out gates is enabled by the respectively associated read out means to transmit a digital word read out from said memory by said respectively associated read out means exclusively of digital words read out from said memory by others of said read out means.

37. An electronic organ as recited in claim 35 wherein:

each of said read out means simultaneously reads out from memory a digital word representing the amplitude information at related sample points of each selected waveshape, and

each of said read out gates is connected at its inputs in common to the outputs of said waveshape selecting gates to transmit the digital words simultaneously read from memory by the respectively associated read out means for all selected waveshapes to said note producing means.

38. An electronic organ as recited in claim 32 wherein there is further provided:

a plurality of read out gates respectively associated with said plurality of read out means, said plurality of read out gates being connected at their inputs in common to the outputs of said memory for each of said groups of digital words, and

each of said plurality of gates is enabled by the respectively associated read out means to transmit a digital word read out from said memory by said respectively associated read out means exclusively of digital words read out from said memory by others of said read out means.

39. Means for storing in digital representation the amplitude of a wave shape at a plurality of spaced points, means responsive to said stored amplitudes for generating a musical note.

40. In an electronic musical instrument of the type wherein a musical sound is generated by repetitively accessing from a memory stored digital words representing the amplitude at selected points along at least a portion of a wave shape, means for simulating the hiss or air sound of a pipe organ comprising:

means for producing an analog signal resembling a step function and having amplitude values related to said accessed words, the steps in said analog signal containing high frequency components, and

means responsive to said analog signal for producing an audible sound having a musical quality related to said wave shape and containing a hiss related to said high frequency components.

41. A musical tone generation system comprising:

means for providing a repetitious digital representation of a wave shape, the repetition rate of said digital representation being manually selectable and corresponding to the frequency of a musical tone, and

means for converting said repetitious digital representation to an audio signal.

42. A system according to claim 41 further comprising:

means for programmatically, arithmetically modifying said digital representations to control the attack and decay characteristics of said audio signal.

43. An electronic musical synthesizer comprising: memory means for storing a plurality of digital words each representing the incremental difference in amplitude between successive ones of a like plurality of amplitude sample points of at least a portion of a wave shape,

first readout means for sequentially accessing said words from said memory means at a first selectable rate related to a first musical note,

conversion means for algebraically adding the amplitude increment represented by each accessed word to the accumulated sum of the amplitude increments represented by previously accessed words and for producing an audio signal corresponding to the values of the resultant accumulated sums.

44. An electronic musical synthesizer according to claim 43 further comprising:

one or more additional readout means for sequentially accessing said words from said memory means at selectable rates related to other musical notes, said memory means being adapted for serially scanned access by said first and additional readout means, and wherein:

said conversion means algebraically adds the amplitude increments represented by each word accessed by any of said readout means to the previously accumulated sum to produce a resultant accumulated sum.

45. An electronic musical synthesizer according to claim 43 wherein said audio signal comprises a step function which steps abruptly from a level representing the previous accumulated sum to a new level representing the resultant accumulated sum, said steps comprising high frequency components which when audibly reproduced resemble a hiss or air sound.

46. Means for storing a plurality of at least a portion of one or more fundamental or harmonic waves in digital representation, and means for repetitiously reproducing said waves to provide musical notes from said stored representation.

ABSTRACT

A digital electronic organ wherein a digital representation of an organ pipe wave shape is stored in a memory. A frequency synthesizer activated by a manual or pedal key produces a clock frequency at Nf , where f is the frequency of the note selected, and N is the number of sample points in the stored wave shape. The digitized wave shape is read out repetitiously at the generated clock frequency and converted to analog form to produce a musical note having a wave shape corresponding to that stored in the memory. Circuitry is provided to sum digitally notes which are played simultaneously; to shape each note in attack and decay using digital operations; and to read out stored multiple wave shapes to implement harmonic and mutation stops.

**REEXAMINATION CERTIFICATE
ISSUED UNDER 35 U.S.C. 307**

THE PATENT IS HEREBY AMENDED AS
INDICATED BELOW.

AS A RESULT OF REEXAMINATION, IT HAS
BEEN DETERMINED THAT:

5 Claims 1-46 are cancelled.
